(57) **CLAIM**

The ornamental design for a cap, as shown and described.

DESCRIPTION

FIG. 1 is a perspective view of a cap according to my new design;

FIG. 2 is a perspective view of the claimed design as shown in FIG. 1, but with the rear flap in an alternate position;;

FIG. 3 is a left side elevation view of FIG. 1;

FIG. 4 is a right side elevation view thereof;

FIG. 5 is a top plan view thereof;

FIG. 6 is a bottom plan view thereof;

FIG. 7 is a front elevation view thereof;

FIG. 8 is a rear elevation view thereof; and,

FIG. 9 is a rear elevation view of the claimed design as shown in FIG. 2.

The wearer's head, neck and shoulders depicted in broken lines in FIGS. 1 and 2 illustrate environmental matter, and form no part of the claimed design. The broken lines shown along the seams and edges of the visor and crown of the claimed design are stitching, and form no part of the claimed design.

The cross-hatching that occurs intermittently on the surfaces of the claimed design represents woven fabric, and is understood to extend across the entirety of the surface upon which it occurs.
